Application April 10, 1935, Serial No. 15,712

13 Claims. (Cl. 179—171)

The present invention relates to circuit arrangements particularly adapted for use in connection with the operation of electron and vacuum tubes of the general types described and claimed in our issued U. S. Patent No. 1,903,569. Still further and more particularly this invention relates to the use of primary and secondary emission electron streams and associated tube and circuit elements and operating potentials, for producing systems having a high degree of operating efficiency and stability. A further object of our invention is to provide an electronic amplifier device capable of producing high gains over frequency ranges varying to all practical intents and purposes from zero to infinite frequency and especially suitable where extremely high frequencies are involved. Still further objects are to provide an amplifying system whereby the action of the tube and the associated circuits may be made substantially independent each from the other. Other and further objects may be observed in the following description.

The general relationship of the electrode structure in such types of electron tubes as will be utilized to describe the essentials of this invention as applied to various circuit arrangements are set forth in our U. S. Patent No. 1,903,569, and various forms of the circuits suitable for operating such a tube are shown by the drawings, wherein,

Fig. 1 is a circuit diagram, including an electron tube to serve as a portion of our amplifying system;

Figs. 2, 3, 4 and 5 are curves showing the relation of certain potentials and currents;

Fig. 6 portrays another operative combination of tube and circuit elements;

Fig. 7 shows a control element acting to influence a secondary emission current stream, and

Fig. 8 shows both the control elements of Figs. 1 and 7 combined in a single operative structure and system for simultaneous amplification of several frequencies.

A better understanding of the invention may be had by making reference to the various figures of the drawings. Referring first to Fig. 1 thereof, the reference character 1 indicates the complete tube structure, here shown in a simple dia-grammatic form. An input circuit indicated at 2, connects with a control element 3, and includes a polarizing battery 4, which is connected to the cathode 5. While, as shown, the cathode is made emissive by thermal means, no restriction is to be placed on the source of emission, and photo electric, radio active, gas ionization or other

sources and methods of obtaining emission may suitably be used. In such a case, control elements other than the grid structure shown at 3 might be used, such as light intensity in case of photoelectric emission, etc. The emission from the cathode 5 is indicated by the arrows 6 and is directed toward a collector plate 7, which in turn is connected back through the potential source 8 to the cathode 5. Under proper conditions, to be hereinafter described, secondary charges are emitted from the collector plate 7 and directed as indicated by the arrows 9 toward the output plate 10. It should be understood at this point that the term "charges" herein used is to be regarded as generic and includes electronic emission, protonic emission and/or any charged body. The charges gathered by the output plate 10 are passed through the load network, which in this case consists of an inductance 11 and a condenser 12, and then through the source of potential 13 back to the cathode 5. The shield 14 is interposed to prevent the flow of the cathode emission 6 directly to the output plate 10 without having the relay action taking place at the collector plate 7. The shield may be connected to the cathode 5 by the source of potential 15.

Fig. 2 shows the current flowing in the cathode at the point 16 with respect to the potential applied to the collector plate 7 by means of the source of potential 8, the potentials on other electrodes being maintained constant. As the potential E_8 is raised, the current I_{16} increases, possibly following reasonably near the well known three halves power law, between the points 17 and 18. Above 18, however, the current flattens out as shown from 18 to 19, instead of continuing on its original trend of 17 to 18 to 20. This flattening is well known in the case of thermal emissive bodies, and is due to the fact that the voltage E_8 is sufficiently high at the point 18 to draw over all the charges emanating from the cathode (at this temperature of operation). Further increase in voltage therefore cannot increase I_{16} and we have a result called saturation. (Temperature saturation, as a further increase of cathode temperature would increase the current I_{16} .)

Considering the collector plate 7 as an emitting body, a curve somewhat similar to that of Fig. 2 may be drawn. This curve, shown in Fig. 3, is plotted between different steady potentials E_{13} applied to the output plate 10 and I_{21} , the current through the point 21 in Fig. 1. In Fig. 3, the voltages on other tube elements were held constant. The charges emitted from the cathode 5, acceler-

ated by the potential E_8 maintained on collector plate 7, strike the collector plate 7 at high velocity and drive off "secondary" charges. These secondary charges are emitted at low velocity and build up a space charge around the collector plate 7. When the potential of the output plate 10 is zero or at a lower value than E_8 , these "secondary" charges fall back into the collector plate 7. Hence, in Fig. 3, the current I_{21} is substantially zero whenever E_{13} is less than E_8 , as shown between the points 22 and 23. After the point 23, however, the current I_{21} rises to the point 24. Up to this point the increasing voltage on the output plate 10 draws over more and more of the low velocity secondary emission from the collector plate 7. At the point 24 substantially all of the secondary emission is taken over to the output plate 10 and from the point 24 to point 25 in Fig. 3, saturation somewhat similar to that shown in Fig. 2 takes place. Inasmuch as a large number of secondary charges may be driven off for each primary charge, the maximum current I_{21} may be many times the cathode emission I_{16} . Beyond the point 25 a new effect comes into play. In increasing the potential E_{13} a gradually changing field pattern of the electrostatic lines of force takes place and the charges transversing the space between the cathode 5 and collector plate 7 are subjected to a strong diverting force as soon as they reach the region beyond the screening action of the shield 14. The momentum acquired by the charges moving from the cathode 5 toward the collector plate 7 is sufficient, with E_{13} at a reasonably low value, to carry them on to the collector plate 7 and so give rise to the gain due to the secondary to primary emission ratio. There comes a value of E_{13} , however, when these charges are diverted around the corner in spite of the protective action of the shield 14, passing directly to the output plate 10. In this case, the secondary emission ratio gain of these particular charges is lost and I_{21} decreases, the limit being the point at which all the primary emission 6 would be pulled around the corner and I_{21} would drop to the value I_{16} . It is obvious therefore that for maximum amplification it is desirable to work between the points 24 and 25. This will be referred to again.

Fig. 4 shows the secondary emission current I_{21} as a function of E_8 , when the potential E_{13} is always maintained within the range corresponding to the maximum value section 24-25 of the I_{21} curve shown in Fig. 3. The current I_{21} starts at the point 28 in Fig. 4 and increases rapidly towards the point 29. An initial value of E_8 is required to produce secondary emission, it being seemingly necessary to impart more than a critical energy state to the particles in the primary emission stream to bring about the ejection of charges from the collector plate 7. Although the primary emission current no longer greatly increases after the point 18 in Fig. 2, the secondary emission ratio continues to go up with increase of potential E_8 . This increase does not appear to be indefinite and tests of numerous materials indicated that points can be reached where increasing the potential E_8 does not produce corresponding increases in secondary to primary emission ratio. The reason for this is somewhat obscure but the action is as though the emission of secondary charges was purely a surface phenomena, and after driving a primary charge against the collector plate 7 hard enough to make a (relatively) large surface splash, further force which might drive the incoming charge deeper,

would dislodge no more surface charges. The effect is not likely one of saturation as an increase in number of primary charges (i. e. value of current) gives a corresponding increase in secondary emission.

Fig. 5 shows a customary curve of output current against reference volts E_g on the grid control element of Fig. 1. In all respects this is quite similar in appearance to the normal triode type of amplifier tube, except that the slope (mutual conductance) is multiplied by the secondary emission ratio. The saturation point 32 on this curve may be due to (temperature) saturation of the primary emission 6, or may be due to the limit of secondary emission 7 which will be drawn over 15 to the output plate by reason of a too low voltage E_{13} on the output plate. (Similar to voltage saturation.) If the potentials are so chosen as to make these various limiting conditions outside the range of normal operation, an extremely satisfactory amplifier will result.

It will be noticed that the curve resulting from the saturation of the secondary emission from the collector plate 7 as shown by the curve between 24 and 25 of Fig. 3, is extremely flat. This means 25 no change of current I_{21} with output plate voltage E_{13} over this range, and consequently, infinite plate impedance. As this is a desirable condition of operation, a further precaution should be noted. Potentials existing across the output load 30 or network, as here shown as inductance 11 and capacity 12, will add to and subtract from the potential E_{13} . To operate between the points 24 and 25 of Fig. 3, it is therefore desirable to choose E_{13} sufficiently above the point 24 and sufficiently 35 below the point 25, so that the variations in potential across the load in the output circuit cannot swing the actual potential on the output plate either below the point 24 or above the point 25.

Fig. 6 shows a multi element tube functioning 40 in the same manner except that a plurality of opposed collector or electron-emitting plates are used to provide more than one step of secondary emission, thereby to still further increase the gain. In Fig. 6, the reference character 33 is used 45 to designate the tube structure containing a cathode 34, a control element 35, a first collector plate 36, a second collector plate 37 and an output plate 38. Shields 39 and 40 are interposed to assist in providing desired potential gradients and to control 50 the flow charges to the desired plates. Sources of potential 35', 39', 41, 42, 43 and 44 are provided, which may largely be common if so desired, in order to obtain between the various elements the desired potentials. The inductance 55 45 and condenser 46 here form an output system, while the input system is indicated at 47. To obtain a desirable condition of amplification, we have found that the collector plate 37 should be maintained at the saturation potential with reference to the collector plate 36, as shown between the points 24 and 25 of Fig. 3. The output plate 38 should also be so maintained with respect to the collector plate 37. The primary emission stream is indicated by the reference character 48, 65 and the resulting secondary emission by the arrows 49. A second step of secondary emission results in the charge stream indicated at 50.

A number of important advantages result from the cooperating elements indicated in Fig. 6. It 70 has been shown by others in the art, that capacity existing between the input and output elements of an amplifier is generally undesired as it may lead to oscillation or degenerative action. The greater the gain in an amplifier, the less 75

such existing capacity must be in order to avoid undesired effects. In the construction of Fig. 1, practically all capacity coupling between the input element 3 and the output element 10 is eliminated by the action of the shield 14. It is possible to conceive, however, that if the gain of such an amplifier be increased enormously, the remaining capacity coupling might reach an undesired point. The construction and associated 10 circuits and potentials indicated in Fig. 6 permit such an enormous gain, as above conceived, to be obtained. In Fig. 1, two elements, the collector plate 7 and the shield 14 serve to reduce the capacity coupling between input and output 15 elements. In Fig. 6, four elements, collector plates 36 and 37, and shields 39 and 40, serve to reduce any possible undesired effects. Thus the same elements which, added to Fig. 1, serve to increase the gain, also reduce the capacity coupling, and the increase in gain is therefore entirely useful and without other deleterious effects.

Another important advantage over present existing amplifiers is apparent in considering the cooperating elements of Fig. 6. In present known 25 methods, an amplifying tube is controlled in some desired manner, the output of this tube is transferred to the control point of a succeeding amplifier tube by means of an electrical network. This network occasionally has the advantage of 30 adding frequency selection to the amplifier (if desired) but may have certain disadvantages among which may be power loss and reduction in efficiency of transmitted signal. Further, if a broad band of frequencies is to be transmitted, 35 it becomes exceedingly difficult to design a translating network to act between amplifying tubes so that the loss in such a network is not more than the gain in the amplifying tubes. Still further, such networks are, in general, of greater in- 40 efficiency at very high frequencies and the problem becomes increasingly difficult. In Fig. 6, however, we show an amplification system, with an input control point, successive stages of amplification linked without the use of electrical net- 45 works as above described, and an output impedance to make use of the resulting gain. As no impedances (electrical networks) are used in the secondary to primary emission gain ratio system, enormous gains can be obtained, almost re- 50 gardless of frequency. As no electrical networks, having variable characteristics with respect to frequency, are used in linking of one amplifying stage of Fig. 6, to the succeeding amplifier stage, very wide bands of frequencies may be uniformly 55 amplified. This is especially useful for carrier current telephony, television, etc. where it may be desirable to amplify several octaves in frequency simultaneously.

A still further advantage is obtained in the 60 cooperating system shown in Fig. 6. It is necessary in present types of amplifying tubes to have rather large currents flow in the tube in order to make them good amplifiers. This is true even though the alternating current components in 65 such a tube used as the first amplifier are extremely small. The direct current component in that and subsequent amplifier tubes should be equal to or greater than the peak alternating current value to avoid cutoff with sinusoidal currents. In the primary emission stream indicated as 48 in Fig. 6, only a small constant current need be provided. This is because the input signals, and the resulting alternating current component of the primary emission stream, is small. After 70 being amplified by the secondary emission action

at the collector plate 36 of Fig. 6, the alternating current component is increased and for correct action, the direct current component must be increased also. However, the collector plate 36 amplifies alternating and direct current alike, and hence, if a proper ratio is obtained in the primary stream, no subsequent overloading can occur and no distortion can result. As noted above, each branch of the electron stream functions as a stage of amplification and the design of a multistage 10 amplifier of the secondary emission type is thus materially simplified since provision against overloading in the first stream branch or stage insures against an overloading in any subsequent stream branch. This is particularly important in 15 the case of a photoelectric source of primary emission, where the intensity and resultant primary emission stream may vary over wide extremes of value.

A still further advantage is present in the sys- 20 tem of Fig. 6 as compared with the normal amplifying system wherein successive amplifier tubes are coupled with electrical networks. As is well known in the art, if a condenser is charged and then discharged into an electrical network having 25 less than a certain critical damping resistance, an oscillatory current results. In general, those networks used for coupling normal amplifier tubes have losses well below the critical damping point, and so produce oscillatory currents whenever a 30 condenser so discharges. As the condensers in such networks are often charged due to transient electrical effects, they equally often contribute undesired oscillatory discharges, causing such transients to hang over and producing more ob- 35 viously disturbing results. Our method of amplification, in eliminating such coupling networks between amplifying stages, eliminates such undesirable effects as above described.

Still other modifications of our amplifying de- 40 vice and system may be utilized as shown in Fig. 7. Here the reference character 51 represents a tube structure, 52 a cathode or charge emitter, 53 is the charge stream so emitted directed toward the collector plate 54 where a secondary charge 45 stream 55 is developed by secondary emission action. This charge stream 55 flows towards the collector plate 56, where a new secondary emission charge stream 57 is produced, which in turn flows to the output plate 58. For the purpose of 50 controlling the resulting charge streams at some point between the first point of origin and the last point of absorption, a control element 59 may be introduced at some point after the source of the first secondary emission stream, and is 55 here shown interposed between the plates 54 and 56. This is a particular advantage when the initial source of primary emission as here represented by the cathode 52 is not a small localized 60 source but is of such a nature as would be difficult to control by the normal control element such as the grid structure shown. This arrangement is also advantageous whenever a changing field potential surrounding the emitter represented here as the cathode 52 will change the fundamental 65 nature, quantity, velocity, continuities of emission, etc. Such effects may be undesired, and as possibly caused by changes in potential of a control element, such a causation is eliminated by the interposition of the secondary emission relay 70 action of the collector plate 54 and electrostatic shielding action of the shield 69. The secondary emission relay action on the collector plate 56, and the electrostatic shielding of the interposed shield 70, serve to completely separate the input 75

grid control element and the output plate, thereby obtaining advantages previously described. Connected to the output plate is a load impedance network, here for example shown as inductance 5 60 and condenser 61. The input network is represented as the inductance 62. Sources of potential 63, 64, 65, 66, 67 and 68 serve to maintain any desired potential on the tube elements. The 10 relative values of such potentials have been to some extent shown, but no limitation on the potentials desired is intended.

It is only a step from Fig. 7 to Fig. 8, where the noted tube structure, operating potentials and associated circuits permit simultaneous amplification of those frequencies associated with more than one source, for example, frequencies F_1 and F_2 . In Fig. 8, the reference character 71 portrays a substantially complete tube structure. The 15 charge emitter, here shown as the cathode 72, produces the charge stream 73 directed toward the collector plate 74. This primary charge stream is subject to control, the means here shown as the grid structure 75. Secondary emission from the collector plate 74 is directed toward another collector plate 77 as shown by the indicating arrows 76. Interposed between the collector plates is another control element, again a 20 grid structure for modifying the secondary emission stream 76. Another stream of new secondary 25 emitted charges comes from the collector plate 77 as indicated by the arrows 79. The output plate 80 absorbs and passes on this charge stream into the output network. As two separate controls are 30 exercised on the charge streams within the structure, separate effects are produced. These may be separated (if desired) by a plurality of networks, each responsive to the initial frequency of control, such as frequencies F_1 and F_2 . Such networks are as shown in the inductance 81 shunted 35 by the condenser 82, and in the inductance 83 shunted by the condenser 84. One input circuit which actuates one control element is shown by the inductance 85, while a second input circuit which actuates a second control element is shown 40 by the inductance 86. Sources of potential 87, 88 and 89 serve to maintain desired potential on the various tube elements. Electrostatic coupling between input control elements 75 and 78 is prevented by the secondary emission relay action 45 of the collector plate 74 and the electrostatic shielding action of the interposed shield 90. Similarly, electrostatic coupling between either of 50 these elements and the plate 80 is prevented by the secondary emission relay action of the collector plate 77 and the electrostatic shielding action of the interposed shield 91.

In Fig. 8, when the various potentials are properly chosen, linear control effects will result and substantial independence of amplification action 55 of the two control elements will be obtained.

The methods of operation contemplated by our invention have been described with reference to certain specific circuits and applications, modifications and uses of the invention other than those herein described fall within the spirit of our invention as set forth in the following claims.

We claim:

1. An electron tube amplifying system comprising an input circuit, an output circuit, an electron tube relay device having a primary electron emitting electrode, an output electrode, and a plurality of electrodes intermediate the primary electron emitting electrode and the output electrode, said intermediate electrodes being adapted when sub-

jected to the action of an impinging electron stream to emit secondary electrons, polarizing means including a voltage source having the positive terminal thereof connected to the output electrode and the negative terminal thereof connected with the primary electron emitting electrode, a plurality of independent connections between each of said intermediate electrodes and said voltage source whereby progressively increasing positive voltages relative to the primary electron emitting electrode may be applied to said intermediate electrodes to cause the development of an electrostatic field within the tube causing the electrons to move progressively from the source to the output electrode and to vary in number in accordance with the number of intermediate electrodes and the secondary emission factor of each, a shield electrode adjacent each intermediate electrode, and connections between the respective shield electrodes and the said polarizing means to apply a positive voltage upon each shield electrode of predetermined value relative to each adjacent intermediate electrode.

2. The system claimed in claim 1 comprising in addition a control electrode and a connection between said control electrode and one of said circuits to control the output from the system.

3. The system claimed in claim 1 comprising in addition a control electrode connected with the input circuit to control the output from the system in accordance with signalling impulses applied to the input circuit.

4. In an amplifier system, the combination with a tube including means for establishing a stream of electrons, a plurality of spaced electrodes adapted to release secondary electrons, a collecting electrode, control grids in the path of the electron stream to said collecting electrode and separated from each other by at least one of said spaced electrodes, a source of polarizing potential and connections from said potential source to the several spaced electrodes and said collecting electrode to establish a potential gradient from one to another of said spaced electrodes with a maximum potential at the collecting electrode, of a plurality of input circuits, an output circuit connected between said collecting electrode and said stream-establishing means, and means connecting each of said input circuits to an individual control grid.

5. In the operation of an amplifying system including a tube having a plurality of electrodes adapted to emit secondary electrons to form a series of successive streams of secondary electrons between a source of primary electrons and a collecting electrode, and a plurality of input circuits having different frequency characteristics, the method of controlling the output at the collecting electrode by the several input circuits which comprises modulating different streams of secondary electrons by the fluctuating voltages developed in the several input circuits.

6. In combination, means for producing a primary electron stream, means including opposed electrode surfaces for producing successive streams of secondary electrons of progressively increasing amplitude from said primary electron stream, a circuit for imparting to one of said electron streams an alternating current frequency characteristic, and an output circuit in which said electron streams develop an alternating current of a frequency controlled by said first circuit.

7. In the process of multiple amplification by the repeated development of streams of sec-

ondary electrons from electrode surfaces located between a source of electrons and an output electrode, the method of controlling the magnitude of the electron stream reaching said output electrode which comprises individually controlling the magnitude of the streams of electrons approaching different electron surfaces.

8. In an electron tube circuit, the combination with a tube including a pair of opposed electrodes each adapted to liberate electrons by secondary emission, means for establishing between said opposed electrodes an electrostatic field for attracting electrons from one electrode to the other, and means including a load circuit external to said tube for utilizing the current resulting from said electron movement, of means including a circuit element external to said tube for determining the frequency of the alternating voltage established by the movement of electrons from one electrode to the other.

9. The combination with an electronic tube, means within the tube for establishing a stream of primary electrons, and a plurality of opposed electrode means for receiving said electron stream and amplifying the same in the form of emitted secondary electrons, of an output circuit connected to at least one of said opposed electrode means, a circuit external to said tube in which an alternating voltage may exist, and means including said second circuit for controlling the magnitude of the electron stream.

10. An electron tube amplifying system comprising the combination with an electron tube device having a primary electron emitting electrode, an output electrode, and a plurality of electrodes intermediate said emitting and output electrode, said intermediate electrodes being opposed to and longitudinally spaced from each other and each having the property when subjected to an impinging electron stream of emit-

ting secondary electrons, means including a source of polarizing potential external to said tube device and connections therefrom to said electrodes to establish an electrostatic field for moving a stream of electrons from said primary electron emitting electrode progressively to said intermediate electrodes and to said output electrode, whereby the number of secondary electrons arriving at said output electrode is dependent upon the number of intermediate electrodes and the secondary emission factor of each, an output circuit connected to said output electrode, and means including an input element external to said tube device for controlling the magnitude of the stream of electrons.

11. An electron tube amplifying system as claimed in claim 10, wherein said tube device includes a shield electrode adjacent certain of said intermediate electrodes, and circuit connections from said shield electrodes to said polarizing potential source for maintaining each shield electrode at a predetermined positive potential with respect to the adjacent intermediate electrode.

12. An electron tube amplifying system as claimed in claim 10, wherein said magnitude controlling means comprises a control grid within said tube device and said input element is connected between said control grid and a tube electrode.

13. An electron tube amplifying system as claimed in claim 10, wherein said magnitude controlling means includes a plurality of input elements, and said tube device includes a plurality of control grids, each input element being connected to an individual control grid and said control grids being spaced apart along the electron stream by at least one intermediate electrode.
